UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE

Application filed January 12, 1931. Serial No. 38,288. Term of patent 14 years.

To all whom it may concern:

Be it known that I, ARTHUR STOCKSTROM, a citizen of the United States, residing in the city of St. Louis and State of Missouri, have invented a new, original, and ornamental Design for Ranges, of which the following is a specification, reference being had therein to the accompanying drawings.

In the accompanying drawings;

Figure 1 is a perspective view of a range showing my new design.

Figure 2 is a perspective view of a range showing my new design, one part of the range shown in open position.

The predominant feature of this design

consists in providing the doors of the stove with ornamentation consisting of narrow parallel panels extending in horizontal alignment across the stove and providing the top burner portion with an inwardly extending cut out portion and the hinged cover with a rectangular projection when closed covering the said top burner portion.

I claim:

The ornamental design for a range, as shown and described.

In testimony whereof, I hereunto affix my signature.

ARTHUR STOCKSTROM.
